UNITED STATES PATENT OFFICE

ROBERT C. MURRAY, OF ST. PAUL, MINNESOTA, ASSIGNOR TO ECONOMICS LABORATORY, INC., OF ST. PAUL, MINNESOTA, A CORPORATION OF DELAWARE

PROCESS FOR MAKING SODIUM RESINATE

No Drawing.

Application filed August 3, 1929. Serial No. 383,426.

The present invention relates to a process for making dry sodium resinate.

An object of the present invention is to simplify and improve a process for making dry sodium resinate.

In order to attain this object, a quantity of rosin is heated until completely melted and is then saponified by slowly adding a predetermined amount of alkali to completely neutralize the rosin. The amount of alkali added is approximately fifty per cent of the amount of rosin used. During the addition of the alkali the mass is stirred so as to prevent the formation of solid masses which might interfere with the complete saponification of the mass. During this mixing process the mass is held at or above one hundred degrees centigrade until the reaction is complete.

The completion of the reaction is indicated by the mass becoming hard, dry, and brittle.

The alkalis used in carrying out this process may be potash, dye, or any other suitable alkali.

A modification of this process of producing dry sodium resinate comprises the melting of a quantity of rosin and the adding of an amount of alkali less than that necessary to completely neutralize the rosin. This alkali is then supplemented by the addition of dry sodium phosphate crystals in excess of the amount necessary to complete the reaction. This will produce dry sodium resinate which will contain tri-sodium phosphate crystals.

This dry sodium resinate is used commercially as an ingredient in soaps and cleaning mixtures for its detergent properties.

Heretofore it has been possible to manufacture dry sodium resinate, but, previous sodium resinates have had a tendency to cake when in use, which tendency does not exist in the dry sodium resinate produced by the present process.

I claim:

The method of producing a dry detergent containing sodium resinate which comprises melting a quantity of rosin, of adding to said melted rosin an amount of caustic alkali less than that necessary to completely neutralize the rosin, of thereafter adding to the mixture

a quantity of dry sodium phosphate crystals slightly in excess of the amount necessary to complete the saponification of said rosin, and of stirring the mass during the addition of said alkali and said dry sodium phosphate.

In testimony whereof I affix my signature.

ROBERT C. MURRAY.
